CLAIM

The ornamental design for a display screen or portion thereof with graphical user interface as shown and described.

DESCRIPTION

The FIGURE is a front view of a display screen or portion thereof with graphical user interface showing our new design.

The dot-dash broken line illustrates a display screen or portion thereof and forms no part of the claimed design. The even-dash broken lines illustrate portions of the graphical user interface that form no part of the claimed design. The grayscale fill illustrates contrast which is part of the claimed design, and is not representative of any particular color.
